UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 31, 1924. Serial No. 729,329.

This invention relates to improvements in novel mechanism designed to permit a fan-folded work-web, such as is used in billing typewriting machines, to be properly gaged 5 according to the length of each printed form on the web, and then detached as fast as they have been typed.

The present invention finds particular embodiment in a standard Underwood type-writing machine wherein provision is made 10 for slitting several folds of a fan-folded web, and auxiliary ink-ribbons are employed for manifolding purposes instead of the usual individual carbon-sheets interleaved 15 between the several plies of the fan-folded web. In this way it has been found possible to get rid of the usual carbon-carrier employed to carry along the work-web towards the platen and also to eliminate the 20 usual table upon which the carbon-carrier travels, thus simplifying the mechanism and reducing its cost.

Heretofore it has been the practice to mount a plurality of fan-fold slitters either 25 on the carbon-carrier or on other traveling mechanism at the rear of the platen, thereby providing means for imparting motions to the slitters for severing the folds 30 of the work-web. It is one of the features 35 of the present invention to still make use of that type of machine described above wherein an auxiliary ink-ribbon replaces the usual manifolding carbon-sheets; and further to provide, as a novel and distinct 40 improvement, a means for performing the slitting function without the use of a carrier or the like upon which the slitting knives are mounted. In carrying out this improvement the slitting knives are fixedly mounted 45 in position just below the printing line of the platen.

Whenever an improvement has been worked in any or all of the foregoing types 45 of machines in the direction of preventing or overcoming the tendency of the platen slipping with respect to the work-web it is 50 designed to carry forward up to printing-line position owing to the inertia induced by the weight of the carbon-carrier or other carrier and the weights of the composite 55 work-web and the carbon-sheets interleaved between the plies thereof, a loop or slack has been produced back of said platen, thus

permitting this looped portion of the work-web to be taken up line by line during the 55 line-spacing action of the platen until the occasion arises for relooping a fresh portion of this web. When the slipping of the platen relatively to the work-web was overcome by means of this loop, the loop was 60 formed by means of the carrier carrying the slitting knives in the type of machine employing the auxiliary ink ribbon to replace the carbon-carrier; otherwise the carbon-carrier was retained with the individual carbon-sheets and means was provided for 65 moving the carbon-carrier simultaneously with the platen during the line-spacing action of the latter in a manner to allow said carbon-carrier to begin its movement just 70 previous to the rotative action of the platen, so that slack is introduced upon the work-web by means of the carrier which is first taken up by the platen as it rotates before carrying the work-web up to the printing 75 line of the machine.

The present invention or improvement employs neither mode of creating slack upon the work-web and for the aforementioned purpose. Means are provided which are 80 selectively controlled according to the various lengths of the printed forms on the work-web for producing a loop upon the work-web of a length equal to that of any of the variable lengths of the printed forms 85 just prior to the same being carried along by the platen to printing-line position, this means including a platen sweep for rapidly effecting a reverse turning of the platen 90 to carry the web rearwardly thereof while a portion of the web is held stationary, whereby to enable the platen to create the loop.

A new problem is introduced in devising the present mechanism that has not heretofore existed, because previously in forming a loop in back of the platen some device was necessary for moving back a portion of the web upon itself while another portion was held in engagement with the platen by means 95 of the pressure rollers at the bottom of the platen; and it was also necessary to perform two separate operations in connection with first gaging the predetermined length of the web corresponding to the length of a printed form thereon before the loop was formed 100 105

and before the typing action occurred, and thereafter again gaging the same printed form of the web after it had been typed, so that it might be detached.

5 The present invention now makes it possible in one operation to gage simultaneously the length of the printed form that is to be looped and advanced to printing-line position for the typing operation, and also to 10 gage the length of the printed form that has already been typed prior to severing the same by means of the usual tearing-off knife, thereby effecting an important economy in such type of machine. This double- 15 gaging action is accomplished by the act of the typist drawing upon the typed portion of the web to bring the same against the leading-edge gage. This operation alone is responsible for gaging two lengths 20 of two printed forms on the web at the same time, so that the typed form is not gaged and detached until after there has been gaged also at the same time with the gaging of the typed form the next succeeding print- 25 ed form that is ready to be typed and looped for that purpose. During the gaging operation referred to, the slitting knives have severed the folds of the web, thus permitting free action of the platen for line- 30 feeding the work-plies between the ribbons.

The present invention by successive stages of operation serves to precondition the work- 35 web for an ultimate severing action as follows:—When the machine is started in use with the work-web properly held in engagement with the platen by the pressure rollers, the web is first drawn upon so that its leading edge is presented against the adjusted gage above the platen until the length of 40 two printed forms of the web has been gaged with the division line between the second and third printed forms located in registration with the edge of a tearing-off knife. Adjustable means are provided for 45 imparting to a handle located adjacent the platen a selected throw depending upon and corresponding to the length of one printed form on the web. The typist actuates this handle, and the result is to pull 50 the gaged portion of the web reversely to the direction of movement in which the web has been fed around and above the platen, so that one of the gaged printed forms is looped in back of the platen ready to be advanced 55 by the platen to printing-line position to be typed upon, while the division line between the other gaged printed form and the one just looped is located in registration with the edge of the tearing-off knife and 60 may be detached. During the typing action the looped printed form is gradually taken up line by line and will occupy the identical position just occupied by that printed and gaged form which has already been de- 65 tached, so that its division line, with the

next preceding form, is located in registration with the tearing-off knife, but before being detached this time the web is drawn again and its leading edge presented against the gage, thus gaging the length of the next 70 printed form about to be looped and then typed. After this is done the handle is again operated, and a loop is formed upon the untyped printed form, and the typed printed form may now be served. 75

A still further feature of this invention is the provision of novel means for positioning the slitters relatively to the platen beneath the printing line of the machine, and to position the auxiliary ink-ribbon there- 80 adjacent. To this end supports are mounted upon the ends of the platen-frame and carry angular arms, the terminals of which provide the slitters, said arms also supporting hooks upon which the ends of the aux- 85 illary ribbon are secured.

Another feature of this invention is the provision of means for preventing a sheet interposed directly between the main and auxiliary ribbons of a typewriting machine 90 from receiving typed impressions upon both sides thereof. Said means is positioned along the length of the auxiliary main ribbons so as to extend across the lines of the sheet to be typed. 95

Other features and advantages will hereinafter appear.

In the accompanying drawings, Figure 1 is a front elevation of the invention positioned upon a typewriting machine. 100

Figure 2 is a fragmental sectional view of one end of Figure 1.

Figure 3 is an end view of a fan-folded web, showing the interposed ink-ribbons dia- 105 grammatically.

Figure 4 is an end elevation of Figure 1, taken on the line 4—4 thereof.

Figure 5 is a view similar to Figure 4, showing the formation of a loop upon a web.

Figure 6 is a front elevation, partly broken away, of means for supporting the auxiliary ribbon and slitters about to be described.

A paper-gage arm or rest 10 is secured at its lower end upon a portion of the platen-frame 11 by means of fasteners 12 engaging a bracket 13 extending across the front of the machine and having integral lugs 14 secured by fasteners 15 to the top plate 11^a of the platen-frame. 16 designates depend- 115 ing webs formed upon the top plate 11^a, and being, respectively, provided with pins 17 projecting through openings 18^a formed upon plates 18, which overlap said webs 16. As means for removably securing the plates 18 upon the platen-frame, screw bolts 19, 120 also mounted upon the webs 16, project through other openings 18^a in the plates 18, and receive the knurled nuts 20 in threaded relation, so as to hold the side plates against vertical displacement from said webs. 125

The plates 18 are formed with depending shanks 21, which are formed integrally with angularly projecting arms 21^a, which project toward each other and toward the center of the machine, and upstanding hooks or fingers 23 are formed upon the arms 21^a at the inner ends of the latter for a purpose hereinafter described. The terminals of said arms 21^a are extended at an angle thereto 5 so as to converge downwardly, having their outer edges 22^a shaped into slitting or cutting edges to form the knives 22. Supplemental hooks or fingers 23^a may also be formed and supported upon the arms 21^a 10 of the plates 18 in a manner shown only diagrammatically in Figure 3. An auxiliary ink-ribbon 27 has its ends 27^a looped or otherwise secured around the hooks or fingers 23, which are preferably extended and 15 enlarged as illustrated, or it may be secured thereupon in the shape of an endless band which may be advanced or fed along by any desirable means not shown. Similar auxiliary ribbons may be mounted upon the auxiliary hooks 23^a by means, such as loops 23^b; these ribbons function as carbons and are interleaved between the plies of a fan-folded web about to be described. 29 designates the usual type-bars supporting the type surfaces 30 which are brought into engagement 20 with the main ink-ribbon 28 that vibrates along the printing line and that makes impressions upon the auxiliary ribbon 27. 31 designates the paper-shelf of usual form on 25 the intake side of a platen 60, extending downwardly around the under side thereof. The upper edge of the shelf has a loop or bight 32. 33 designates a base-plate, which is secured by fasteners 34 to the under side 30 of said shelf, said plate having an upwardly-extending arm 35 carrying a rod 36 on which are secured holders 37 having trunnions 38, upon which are snugly fitted ears 39 on the looped portion 40 of a breast plate 41 extending upon the opposite side of the shelf, with its terminal resting thereupon. 45 A similar breast plate 41, with the described attachments for engaging said shelf, is also located upon the shelf, so that the two breast plates may be adjusted transversely of the shelf by means of the holders 37 slidably 50 engaging the rod 36. Guide-flanges 42 are preferably struck upwardly at right angles upon one longitudinal edge of each breast plate 41 and terminate short of one end thereof, and at this end there is looped around the same edge upon which the flanges 42 are formed members 43, also providing guides in continuation of the guide-flanges, 55 because the bights of the looped members 43 are substantially in alignment with said flanges. The bends 44 of the looped members 43 extend laterally toward the medial line of said breast plates and are formed 60 with downwardly-extending leaf-springs 45 projecting longitudinally of said breast plates. The fingers 45^a of said springs yieldably engage said breast plates, so that a fan-folded web or other sheet 46 moving upon said shelf is caused to engage the looped portion 40 of said breast plates, which extend around the looped portion or bight 32 of the shelf, the looped members 43 being secured by fastenings 44^a to the looped portion 40 of the breast plates. 70

A standard or pin plate 47 extends upwardly and is supported upon one of the top plates of the platen-frame, and is formed with an arcuate series of holes 48 receiving a stop pin 48^a, which is removable to selectively determine the extent of movement of a handle lever 55, which is initially positioned against another stop pin 49 also secured upon the standard 47. A lug 50 depends from the platen-frame, which carries a fulcrum pin 51 having a head 52, and operatively and fixedly coiled around said pin or hub is a spring 53 having one terminal or finger 54 secured upon the top plate 11^a at 45^b, and having its opposite terminal or finger 54^a secured upon the lever 55, which carries the usual finger-piece 56. A sector gear 57 is carried by or formed upon the lower end of the lever 55, which is fulcrumed upon the fulcrum pin 51. This sector gear 57 is permanently in mesh with a pinion 58 loosely mounted upon a platen-shaft 59 upon which the platen 60 is fast, so as to rotate therewith. The platen sleeves 61 are secured around the shaft 59 by fasteners 62, and upon this same shaft, but spaced away from one of the sleeves 61, is a collar 63 also fixedly secured upon the terminal of said shaft 59 by fasteners 65, so that by turning a hand-knob 64, mounted upon the collar 63, the platen-shaft 59 is rotated and with it the platen 60, this rotation occurring independently of the pinion 58 during the line-spacing action of the platen for the purpose of feeding the web 46 beyond or above printing-line position. A ratchet-wheel 66 is fixed upon the collar 63 so as to rotate therewith. A suitable clutch is provided for causing the ratchet-wheel to move when the sector gear 57 is actuated. It will be seen that the collar 63 holds another collar 67, (fixed upon, so as to rotate with, the pinion hub 58^a) and the pinion itself against longitudinal displacement from the shaft 59. The clutch consists of a pawl 70 formed on one arm of a bell-crank lever 70^a fulcrumed upon a pin 69 secured to an arm or lever 68 carried by the collar 67, the other arm 73 of said lever 70^a providing an operating piece and engageable by the toe or abutment 77 of a hooked shank or arm 76 disposed concentrically with the pinion 58 and carried by an arm 75 secured by fasteners 74 upon the sector gear 57. Normally the spring 53 holds the lever handle 55 in the position 75

125

130

shown clearly in Figure 4 against the pin 49, thereby disposing one end of the sector gear 57 to mesh with the pinion 58, and causing the toe 77 of the hook 76 to tilt the lever arm 73 to cause the pawl 70 to be disengaged from the ratchet teeth of the ratchet-wheel 66 against the tension of a leaf-spring 71 coiled around the pin 69, with one end pressing the pawl against the ratchet teeth and with its other end secured onto the arm 68. But for the engagement of the hook 76 with the lever arm 73, the pawl would be permanently in engagement with the ratchet and in a position to drive the same around with it for rotating the platen. The arm 68 is constrained to move with the pinion 58 in a clockwise direction as distinguished from the counterclockwise movement which the platen has as it is line-fed, this movement being imparted to the pinion by the sector gear 57, but when all the parts are at rest the pawl 70, as explained before, is out of engagement with the ratchet-wheel 66, so that even after the platen is being line-fed 25 rotatably in a counterclockwise direction, the position of the sector gear, pinion and pawl will remain undisturbed.

The tearing-off knife 78 is positioned as shown in Figure 4 above the printing line 30 and above the ribbons, while the slitters or knives 22 are positioned immediately below said ribbons. The usual pressure rollers 25 and 26 hold the traveling web tensioned against the under side of the platen 60 in 35 the usual way. Adjustably mounted upon the gage or paper bar 10 is a gage 79 located in adjustable position by means of a set-screw or knurled nut 80. Formed upon the arms 21^a of the plates 18 are hooks 81 for 40 holding the ends of a shield 82, which is in the shape of a strip extending in longitudinal alignment with the auxiliary ribbon or ribbons 27 as the case may be and in front thereof. The tearing-off knife 78 is secured 45 at its opposite ends by fasteners 78^a upon the lugs 83 formed integrally upon the web 16, as shown in Figure 1.

In operation the fan-folded web, positioned as hereinbefore described, is unrolled 50 or unravelled from its source of supply and the folds of the web slit in any convenient manner a sufficient distance to permit threading the plies between the auxiliary ribbons. The web is led up over and around the loop 55 40 of the breast plates 41, so that the opposing edges thereof are maintained against the guide flanges 42, which have been adjusted upon the shelf, and so that the web passes between the spring-fingers 45^a and the shelf, 60 and is pressed under tension against the latter as it moves, or may be held stationary at this point. The web is drawn down from the points where it is held by the spring-fingers 45^a and may then be fed around by 65 the rotatable platen 60, so as to cause the

plies of the web to move past and between the auxiliary ink-ribbons 27 with one of these plies between the main ribbon 28 and the next adjacent ink-ribbon 27. Beyond the ribbons and upwardly therefrom the webs are fed along by the platen to a point sufficiently above the tearing-off knife 78 to permit the leading portions of the web to be grasped and pulled upward toward the gage 79. Thus the slitting knives 22 which project into the folds of the web 46 are caused to sever or slit these folds during the upward pull on the web.

The leading end of the web is brought to position against the gage 79, as shown in Figure 4, where the gage is spaced away from the edge of the tearing-off knife 78 a distance equal to the length of two printed forms on the web, designated, respectively, A and B, the division line between these forms being designated B'. In this position of the printed forms A and B, the form A may have already been typed or not, but the form B has not been typed and is about to be looped, for the purpose hereinbefore explained, and then typed.

In order to bring the form A back to the tearing-off knife 78, the typist imparts a variable throw or movement upon the lever 55 by means of the finger-piece 56, so as to cause the lever to move angularly of the standard 47 until stopped predeterminedly of the pin 48^a that limits its further movement or progress, it being understood that the handle is automatically returned against the pin 49 by the spring 53. As soon as the lever 55 is thus actuated and plays between the pins 49 and 48^a, the sector gear 57 moves and causes the pinion 58 to turn in a platen-reversing direction, thereby carrying the arm 68 along with it, and at the same time the hook 76 is retracted from the lever arm 73, whereupon the spring 71, which has its terminal 72 secured to lever 68, will cause the pawl 70 to click into engagement with the teeth of the ratchet-wheel 66 during the continued movement of the pinion, so that the ratchet begins to turn with the platen while the web is engaged by the spring-fingers 45^a under tension, and also pressed under tension against the platen by the pressure rollers 25 and 26, so that during this rotative movement of the platen 60 the web begins to move reversely or towards the spring-fingers 45^a, and this causes the un-typed printed form B to be carried along downwardly relatively to the gage or paper bar 10 around said platen and to pile up or be slackened in the form of a loop 46^a in back of said platen or between said platen and the spring-fingers 45^a upon the shelf 31; and by the time that the movement of the lever is stopped form B has been completely looped, and the division line B' between forms A and B has been brought into

accurate registration with the tearing-off knife 78, so that the form A may be detached along the division line by said knife from said printed form B.

5 Just before the lever 55 comes to rest automatically upon the pin 49, the toe 77 of the hook 76 has engaged the lever arm 73 and tilted the same to cause the pawl 70 to be retracted from engagement with the teeth 10 of the ratchet-wheel 66, and when the lever reaches its final position and rests upon the pin 49 the pawl remains in this position, thereby allowing the platen 60 to be rotated during its line-space action by means of the 15 usual hand-knob 64 to take up the looped portion 46^a of the web, which is the untyped form B, until this form has been completely typed and occupies the position shown in Figure 5. The looped and untyped portion 20 of the web is designated 46^b in Figure 5. The typist now takes hold of form B already typed and does not detach it, but he draws the same until its leading edge engages the adjustable gage 79, as shown in 25 Figure 4. The lever 55 is again actuated as described, and this time form C, which has occupied the same position as form B after the latter has been pulled up to the gage, is looped behind the platen and now form B is 30 detached along the tearing-off knife 78. In a similar manner the platen is operated over and over again to form each separate loop as required.

In Figure 6 the purpose of the shield 82, 35 which is shown in longitudinal alignment with the auxiliary ink-ribbon 27 and in back of the main ribbon 28, and which has a ply of the web between it and the main ribbon, is to receive the typed impressions from the 40 main ribbon 28, which it transmits through the adjacent ply of the web to the ink-ribbon 27, so that the ply will not receive any carbon impressions upon any but the side intended to be read. The opposite ends of shield 82 45 are operatively looped or otherwise secured upon the auxiliary hooks or fingers 81 formed on the arms 21^a of the plates 18.

Variations may be resorted to within the scope of the invention, and portions of the 50 improvements may be used without others.

Having thus described my invention, I claim:

1. In a fan-fold typewriting machine, in combination, a revoluble platen, a main ribbon, auxiliary ribbons, fold-slitting knives beneath the ribbons, a web-shearing knife above the ribbons, a gage against which the leading edge of the web is brought to position, said gage spaced two form-lengths 55 above the shearing knife, a platen sweep for reversely turning the platen, and means for holding the web at a point on the intake side of the platen.

2. In a fan-fold typewriting machine, in 60 combination, a revoluble platen, a main rib-

bon, auxiliary ribbons, fold-slitting knives beneath said auxiliary ribbons, a web-shearing knife above said ribbons, a leading-edge gage two form-lengths above the shearing knife, a platen sweep associated with the 70 platen and movable between selectable positions for reversely turning the platen, and resilient fingers lightly pressing upon the web on the intake side of said platen.

3. In a fan-fold typewriting machine, in 75 combination, a revoluble platen, a main ribbon, auxiliary ribbons, fold-slitting knives beneath said auxiliary ribbons, a shearing knife above said ribbons, a leading-edge 80 gage two form-lengths above the shearing knife, a platen sweep associated with the platen and movable between selectable positions for reversely turning the platen, resilient fingers lightly pressing upon the web on the intake side of said platen, and side 85 gages associated with said resilient fingers.

4. In a fan-fold typewriting machine, in combination, a revoluble platen, a paper-table at the intake side of the platen, a main 90 ribbon, auxiliary ribbons, fold-slitting knives immediately below said ribbons, a shearing knife above the auxiliary ribbons, a leading-edge gage against which the web is positioned two form-lengths above the 95 shearing knife, a pinion associated with the platen, a sector-gear meshing with said pinion, a lever for operating the sector-gear whereby to reversely turn the platen, resilient fingers associated with the rear paper-table and engaging the incoming portion 100 of the web, and side gages associated with the fingers for guiding the web.

5. In a fan-fold typewriting machine, in combination, a revoluble platen, a paper-table at the intake side of the platen, a main 105 ribbon, auxiliary ribbons, fold-slitting knives immediately below said ribbons, a shearing knife above the auxiliary ribbons, a leading-edge gage against which the web is positioned two form-lengths above the shearing 110 knife, a pinion associated with the platen, a sector-gear meshing with said pinion, a lever for operating the sector-gear, whereby to reversely turn the platen, resilient fingers associated with the paper-table and engaging the incoming portion of the web, side gages 115 associated with the fingers for guiding the web, and adjustable stops for controlling the extent of movement of said lever.

6. In a fan-fold typewriting machine, in 120 combination, a revoluble platen, a main ribbon, auxiliary ribbons, fold-slitting knives in advance of the ribbons, a shearing knife above said auxiliary ribbons, a gage two 125 form-lengths above the shearing knife, and means for creating a loop of loose web behind the platen and for bringing the division line of the first form down to the shearing knife, said means including a pinion revoluble on the platen-shaft, a sector-gear 130

- meshing with said pinion, clutch mechanism between said pinion and the platen, means normally maintaining said clutch mechanism ineffective, said sector-gear being 5 movable to cause said clutch mechanism to become effective and to then move the platen in reverse direction, and means for holding the web at a point on the intake side of the platen.
10. In a fan-fold typewriting machine, in combination, a revoluble platen, feed-rolls, auxiliary ribbons, fold-slitting knives positioned at a point between the feed-rolls and the ribbons, a shearing knife above the ribbons, a gage-staff, a gage thereon for the leading edge of the web, said gage spaced two form-lengths above the shearing knife, means for reversely turning the platen, including a handle swingable between two positions and a clutch connecting said handle with the platen, the clutch being ineffective when the handle is in normal position, said clutch becoming effective upon actuation of the handle, and means for holding the web 15 on the intake side of the platen.
15. In a fan-fold typewriting machine, in combination, a revoluble platen, a shearing knife, a gage two form-lengths above the shearing knife, means for reversely turning the platen a distance to bring the first form down to the shearing knife and carry the second form to the rear of the platen, and means co-operating with said platen to cause 20 said second form to be looped.
20. In a fan-fold typewriting machine, in combination, a revoluble platen, a main ribbon, auxiliary ribbons, fold-slitting knives beneath the ribbons, a shearing knife above the ribbons, a leading-edge gage two form lengths above the shearing knife, a handle swingably mounted on the platen-frame, normally ineffective clutch mechanism between said handle and the platen, said clutch mechanism becoming effective upon actuating said handle to 25 reversely turn the platen to bring the second form to printing position and the first form down to the shearing knife, and means for adjusting the throw of said handle.
25. In a fan-fold typewriting machine, in combination, a revoluble platen, a main ribbon, auxiliary ribbons, fold-slitting knives immediately beneath the ribbons, and means 30 operable for reversely turning the platen a predetermined distance to bring the first form down to the shearing knife and the second form to printing position.
30. In a fan-fold typewriting machine, in combination, a revoluble platen, a main ribbon, auxiliary ribbons, and fold-slitting knives adjacent to and in advance of the printing line.
35. In a fan-fold typewriting machine, in combination, a revoluble platen, a main ribbon, auxiliary ribbons, a plurality of auxiliary ribbons, fold-slitting knives beneath the auxiliary ribbons, a severing knife above the auxiliary ribbons, a gage two form-lengths above the severing knife, and means 40 for rotating the platen in a reverse direction, said means including a handle rockably mounted on the platen-carriage, adjustable stops associated with the handle for limiting the swing thereof, a sector-gear carried by 45 said handle, a pinion freely revoluble on the platen-shaft and meshing with said sector-gear, a ratchet-wheel fixed to the platen, an arm carried by said pinion, a pawl pivoted to said arm, means for throwing the pawl into engagement with the ratchet-wheel, and means associated with said sector-gear and normally holding the pawl out of engagement with the ratchet-wheel, said handle operable to effect engagement of the pawl with the ratchet-wheel and then to cause a 50 reverse turning of the platen.
40. In a fan-fold typewriting machine, in combination, a revoluble platen, a main ribbon, auxiliary ribbons, fold-slitting knives beneath the auxiliary ribbons, a shearing knife above the ribbons, a leading-edge gage two form lengths above the shearing knife, and a platen sweep for reversely turning the platen a predetermined distance to bring the division line of the first form down to the shearing knife and to return the second form 55 to printing position.
45. In a fan-fold typewriting machine, in combination, a platen-frame, a revoluble platen, feed-rolls, a main ribbon, auxiliary ribbons, fold-slitting knives interposed between the ribbons and the feed-rolls, a shearing knife above the ribbons, a leading-edge gage two form lengths above the shearing knife, a handle swingably mounted on the platen-frame, normally ineffective clutch mechanism between said handle and the platen, said clutch mechanism becoming effective upon actuating said handle to 60 reversely turn the platen to bring the second form to printing position and the first form down to the shearing knife, and means for adjusting the throw of said handle.
50. In a fan-fold typewriting machine, in combination, a revoluble platen, a main ribbon, auxiliary ribbons, a shearing knife above the ribbons, a leading-edge gage above the shearing knife, fold-slitting knives immediately beneath the ribbons, and means 65 operable for reversely turning the platen a predetermined distance to bring the first form down to the shearing knife and the second form to printing position.
55. In a fan-fold typewriting machine, in combination, a revoluble platen, a main ribbon, auxiliary ribbons, and fold-slitting knives adjacent to and in advance of the printing line.
60. In a fan-fold typewriting machine, in combination, a revoluble platen, a main ribbon, auxiliary ribbons, a plurality of auxiliary ribbons, and fold-slitting knives beneath the auxiliary ribbons.
65. In a fan-fold typewriting machine, in combination, a revoluble platen, a series of ribbons at the printing line, a gage above said ribbons, and fold-slitting knives beneath the ribbons.
70. In a fan-fold typewriting machine, in combination, a revoluble platen, a main ribbon, auxiliary ribbons, and fold-slitting knives adjacent to and in advance of the printing line.
75. In a fan-fold typewriting machine, in combination, a revoluble platen, a main ribbon, auxiliary ribbons, and fold-slitting knives adjacent to and in advance of the printing line.
80. In a fan-fold typewriting machine, in combination, a revoluble platen, a main ribbon, auxiliary ribbons, and fold-slitting knives adjacent to and in advance of the printing line.
85. In a fan-fold typewriting machine, in combination, a revoluble platen, a main ribbon, auxiliary ribbons, and fold-slitting knives adjacent to and in advance of the printing line.
90. In a fan-fold typewriting machine, in combination, a revoluble platen, a main ribbon, auxiliary ribbons, and fold-slitting knives adjacent to and in advance of the printing line.
95. In a fan-fold typewriting machine, in combination, a revoluble platen, a main ribbon, auxiliary ribbons, and fold-slitting knives adjacent to and in advance of the printing line.
100. In a fan-fold typewriting machine, in combination, a revoluble platen, a main ribbon, auxiliary ribbons, and fold-slitting knives adjacent to and in advance of the printing line.
105. In a fan-fold typewriting machine, in combination, a revoluble platen, a main ribbon, auxiliary ribbons, and fold-slitting knives adjacent to and in advance of the printing line.
110. In a fan-fold typewriting machine, in combination, a revoluble platen, a main ribbon, auxiliary ribbons, and fold-slitting knives adjacent to and in advance of the printing line.
115. In a fan-fold typewriting machine, in combination, a revoluble platen, a main ribbon, auxiliary ribbons, and fold-slitting knives adjacent to and in advance of the printing line.
120. In a fan-fold typewriting machine, in combination, a revoluble platen, a main ribbon, auxiliary ribbons, and fold-slitting knives adjacent to and in advance of the printing line.
125. In a fan-fold typewriting machine, in combination, a revoluble platen, a main ribbon, auxiliary ribbons, and fold-slitting knives adjacent to and in advance of the printing line.
130. In a fan-fold typewriting machine, in combination, a revoluble platen, a main ribbon, auxiliary ribbons, and fold-slitting knives adjacent to and in advance of the printing line.

- ribbon, a series of auxiliary ribbons stretched across the platen, shields in front of the ribbons, the latter overextending the shields at both ends thereof, and fold-slitting knives 5 in advance of the printing line.
18. In a typewriting machine, in combination, a revoluble platen around which a fan-folded work-web may be fed, feed-rolls beneath the platen, auxiliary ribbons 10 tending the lengths of said platen at the printing line thereof, and web-slitting knives between the feed-rolls and the auxiliary ribbons, whereby to sever the folds of the web as the web-plies are drawn upwardly 15 in interleaved relation with all of said ribbons.
19. In a fan-fold typewriting machine, in combination, a revoluble platen, a main ribbon, auxiliary ribbons, and fold-slitting 20 knives closely adjacent the ribbons and relatively disposed in advance of the same.
20. In a typewriting machine, the combination of a platen-frame, a shaft rotatably mounted thereon, a rotatable platen fast 25 on said shaft, a pinion freely rotatable on said shaft, an arm carried by said pinion, a ratchet-wheel fixed upon said shaft, a pawl mounted on said arm, means carried by said arm for urging said pawl into engagement with said ratchet-wheel, a sector-gear meshing with said pinion, a handle 30 for actuating said sector-gear, and an abutment rigidly secured to said handle and disposed to directly engage and hold said 35 pawl out of engagement with said ratchet-wheel when said handle is in normal position, the abutment being withdrawn from the pawl when said handle is moved from said normal position.
- 40 21. In a typewriting machine, the combination of a shaft, a platen fast on said shaft, a pinion freely rotatable on said shaft, an arm fast on said pinion, a bell-crank lever on said arm, a pawl carried by one 45 arm of said bell-crank lever, the other arm of the bell-crank lever providing an operating piece for the pawl, a ratchet-wheel fast on said platen, a spring normally holding 50 said pawl in contact with said ratchet-wheel, a gear meshing with said pinion, a spring associated with said gear and holding it in normal position, a handle carried by said gear, and an arm rigidly secured to 55 said handle to move therewith and terminating in an abutment which engages said operating piece of the pawl to hold said pawl out of engagement with said ratchet-wheel against the tension of the pawl-holding 60 spring, when said handle is in normal position, said handle being effective when moved from said normal position to cause the abutment to be withdrawn from said pawl-operating piece.
- 65 22. In a typewriting machine, the combination of a paper-shelf, a platen around which may be fed a work-web, tensioning means located at the upper end of said shelf for lightly pressing said web in engagement with the shelf as it is fed around by the 70 platen, an operating handle, and means interposed between said handle and the platen for causing said platen to return a portion of said web in the form of a loop upon itself, so that the loop is introduced between 75 said tensioning means and said platen.
23. In a typewriting machine, the combination of a revoluble platen, a paper-shelf disposed thereadjacent, side gages adjustably mounted transversely of said shelf and guiding the opposite edges of a web engaged by said platen, springs carried by said side gages and applying light pressure upon said web against said shelf, and manually-operated means for rotating said platen whereby to return a portion of said web upon itself to produce a loop of web between said springs and said platen, said loop being maintained by reason of the web holding 80 action of said springs.
24. In a typewriting machine, in combination, a revoluble platen, a series of ink-ribbons extending along the printing line thereof, and supports upon which the ends 85 of said ribbons are detachably secured, said supports also including slitting knives for severing the folds of a fan-folded work-web drawn upward around the platen with the separated plies threaded between the ribbons.
25. A fan-fold typewriting machine, including, in combination, a platen-frame, a revoluble platen therein, a plurality of ink-ribbons adjacent the platen along the printing line formed into loops at their extremities, projections mounted on said frame adjacent the platen to engage said loops and support said ribbons, and fold-slitting knives disposed beneath the ribbons in adjacent relation to said projections.
26. A fan-fold typewriting machine including, in combination, a frame and a revoluble platen therein, ink-ribbons disposed along the printing line of the platen, having loops upon their extremities, and supports upon said frame adjacent the extremities of said platen including fingers to support said loops extending beyond the adjacent edges of the loops and enlarged to form arms projecting beneath said ribbons and terminating in fold-slitting knives conditioned to slit the folds of a fan-folded work-web before the same reaches said ribbons.
27. A fan-fold typewriting machine including, in combination, a frame and a revoluble platen therein, a fan-folded work-web conditioned to be held in contact with said platen, a plurality of ink-ribbons disposed along said platen and provided with loops upon their ends, removable supports 120
- 130

mounted on the aforesaid frame including vertical fingers extending above the adjacent edges of the loops and terminating in divergently directed hooked ends, and arms 5 extending inwardly beneath said ribbons and terminating in fold-slitting knives conditioned to slit the folds of the aforesaid work-web below said ribbons.

28. In a typewriting machine, in combination,

10 a revoluble platen, a platen-frame, a plurality of ink-ribbons extending along the printing line, removable supports carried by the platen-frame adjacent both ends of the platen, said supports including upstanding 15 hooks around which the ends of the ribbons are looped, ribbon-shields overlying said ribbons, and hooks carried by said supports and upon which the ends of said shields are looped.

15 29. In a fan-fold typewriting machine, in combination, a revoluble platen, a platen-frame, ink-ribbons extending along the printing line, and means for supporting said ribbons by their outer ends, including removable supports carried by the platen-frame, the supports including arms directed inwardly beneath the ribbons and terminating in fold-slitting knives, and supporting fingers carried by said arms for receiving the 25 ends of the ribbons, each support being formed as a unit with its associated knife and finger.

30 30. In a typewriting machine, in combination, a revoluble platen, a platen-frame, ink-ribbons extending along the printing line, and means for supporting said ribbons by their outer ends, including removable supports carried by the platen-frame, each support having an arm directed inwardly beneath the ribbons, and supporting fingers projecting from said arms for receiving the ends of the ribbons, said arms terminating in slitting knives for severing the folds of a fan-folded work-web pulled upwardly 40 around the platen.

45 31. In a fan-fold typewriting machine, in combination, a revoluble platen, a platen-frame, a removable support carried at each side of the platen-frame, each support including an arm directed inwardly beneath the ribbons, the arms being inclined downwardly adjacent their ends and having the lower edges thereof sharpened to form inclined fold-slitting knives, and a pair of upstanding ribbon-holding and shield-holding fingers positioned abreast along each support.

50 32. A fan-fold typewriting machine, including, in combination, a platen-frame and 55 a platen mounted therein, a fan-folded work-web conditioned to be held upon said platen, a plurality of ink-ribbons disposed along the printing line of said platen, ribbon-shields of different relative lengths than 60 said ribbons located in proximate relation

thereto, and supports adjacent the extremities of said platen including converging arms terminating in fold-slitting knives and provided with fingers disposed along the printing line at relative distances corresponding with the different lengths of said 70 ribbons and shields, said knives being disposed to slit the folds of the aforesaid work-web beneath said ribbons.

75 33. In a typewriting machine, in combination, a revoluble platen, a series of ink-ribbons extending the length of the platen along the printing line, hooks adjacent the platen-ends upon which the ends of said ribbons are received and supported, shields 80 overlying each of said ribbons, and hooks upon which the ends of said shields are supported, whereby to be attachable or detachable independently of said ribbons.

85 34. In a typewriting machine, the combination of a platen-frame, plates removably secured upon the ends of said frame, angular arms carried by said plates projecting toward each other, a pair of hooks carried upon each of said arms, respectively, perpendicularly thereof, an ink-ribbon having its opposing ends looped upon the inner hooks, and a shield having its opposing ends secured upon the outer hooks of said plates so as to be positioned in front of and in 90 longitudinal alignment with said ribbon.

95 35. In a typewriting machine, the combination of a platen-frame having side members, a pair of plates removably secured upon said members, angular arms carried by 100 said plates and projecting towards each other, and angular slitting knives formed terminally upon said arms and converging downwardly.

105 36. In a typewriting machine, the combination of a platen-frame having side members, a pair of plates secured upon said side members and depending therefrom, angular arms carried by said plates and projecting towards each other, upwardly-extending 110 hooks formed upon said arms respectively, an ink-ribbon supported removably upon said hooks, and angular slitting knives carried by said arms, said knives having their cutting edges converging downwardly.

115 37. A typewriting machine including, in combination, a platen, an ink-ribbon, a shearing knife disposed above said ribbon, a leading edge gage spaced two form-lengths above said knife, a work-web having a series of equal forms thereon, and a platen-sweep for registering the first form with said knife and looping a portion of said web behind the platen.

120 38. A typewriting machine including, in combination, a revoluble platen, an ink-ribbon adjacent the same, a shearing knife above said ribbon, a leading edge gage spaced two form-lengths above said shearing knife, resilient web-retaining fingers lo- 125 130

- cated on the intake side of the platen, and a platen-sweep to reversely rotate the platen to loop a work-web between said web-retaining fingers and said platen.
- 5 39. A fan-fold typewriting machine including, in combination, a rotatable platen, an ink-ribbon adjacent the same, a shearing knife above the same, a leading edge gage spaced two form-lengths above the shearing knife, a fan-folded work-web for said machine, and means to withdraw said web from said gage to register a predetermined point within the leading edge with the shearing knife and simultaneously loop a portion of said web between said web-retaining fingers and said platen.
- 10 40. A fan-fold typewriting machine including, in combination, a revolute platen, an ink-ribbon adjacent the same, resilient web-retaining fingers located on the intake side of the platen, fold-slitting knives spaced apart adjacent said platen below said ribbon, a shearing knife above the ribbon, a leading edge gage disposed two form-lengths above the shearing knife, and a sweep associated with said platen conditioned to reversely rotate the same and withdraw a web from said gage.
- 15 41. A fan-fold typewriting machine including, in combination, a revolute platen, resilient web-retaining fingers located on the intake side of the platen, an ink-ribbon adjacent said platen, auxiliary ribbons disposed along the platen, fold-slitting knives beneath said ribbons, a shearing knife above the ribbons, a leading edge gage spaced above said shearing knife, and a platen-sweep whereby the platen may be reversely turned to withdraw the leading edge of a work-web from the gage.
- 20 42. A typewriting machine including, in combination, a revolute platen, an ink-ribbon adjacent the same, resilient web-retaining fingers located on the intake side of the platen, a shearing knife above the ribbon, a leading edge gage spaced above said shearing knife, and a platen-sweep to reversely rotate the platen in order to withdraw a work-web from said gage and loop a portion of the web between said web-retaining fingers and said platen.
- 25 43. A fan-fold typewriting machine including, in combination, a revolute platen, an ink-ribbon adjacent the same, resilient web-retaining fingers on the intake side of the platen, fold-slitting knives spaced apart adjacent said platen, a shearing knife above said ribbon, a leading edge gage spaced two form-lengths above said shearing knife, a fan-folded work-web for said machine, and means to withdraw said web from said gage to register a predetermined point within the leading edge with the shearing knife and simultaneously loop a portion of said web between said web-retaining fingers and said platen.
- 30 44. A typewriting machine including, in combination, a revolute platen, an ink-ribbon adjacent the same, a shearing knife located above the ribbon, a leading edge gage spaced above said knife, and means to reversely move said platen to withdraw the first form of a work-web from said gage and register the same with said knife, and move the second form to printing position and loop said web on the intake side of the platen.
- 35 45. A fan-fold typewriting machine including, in combination, a revolute platen, a main ink-ribbon, an auxiliary ribbon relatively stationary with respect to the line-spacing movements of said platen, a shearing knife disposed above said ribbon, fold-slitting knives beneath the same ribbon, and a leading edge gage spaced two form-lengths above said shearing knife, there being means to withdraw a work-web from said gage.
- 40 46. A fan-fold typewriting machine including, in combination, a revolute platen, a main ink-ribbon, an auxiliary ink-ribbon, a shield overlying said latter ribbon, said ribbon and shield being relatively stationary with respect to movements of said platen, and fold-slitting knives spaced apart beneath said auxiliary ribbon.
- 45 47. A fan-fold typewriting machine including, in combination, a revolute platen, a main ink-ribbon, an auxiliary ribbon having a superposed shield and being stationary relatively to rotative movements of said platen, fold-slitting knives spaced apart beneath said auxiliary ribbon, a shearing knife above said ribbon, and a leading edge gage spaced more than a normal form-length above said shearing knife, there being means to withdraw a work-web from said gage.

JOHN WALDHEIM.
